UNITED STATES PATENT OFFICE.

WILLIAM WALLACE SWAN, OF ANDOVER, DAKOTA TERRITORY.

REAMER.

SPECIFICATION forming part of Letters Patent No. 397,525, dated February 12, 1889.

Application filed May 19, 1888. Serial No. 274,393. (No model.)

To all whom it may concern.

Be it known that I, WILLIAM WALLACE SWAN, a citizen of the United States, residing at Andover, in the county of Day and Territory of Dakota, have invented a new and useful Improvement in Reamers, of which the following is a specification.

My invention relates to an improvement in reamers for boring Artesian and oil wells; and it consists in the peculiar construction and combination of devices, that will be more fully set forth hereinafter, and particularly pointed out in the claims.

The object of my invention is to provide a reamer with laterally-expansible bits which are adapted to be automatically adjusted, so as to enlarge the diameter of the bore below the casing-pipe, and thereby permit the latter to be lowered in the well.

In the accompanying drawings, Figure 1 is a side elevation of my improved reamer, showing the same arranged in a well in position for boring the same, the pipe-casing being shown in section. Fig. 2 is an edge view of the same. Fig. 3 is a side elevation of the same with one of the side plates and locking-plates removed.

A represents the body of the reamer, which is provided with a longitudinal recess, B, which is rectangular in cross-section, and extends from within a suitable distance of the upper end of the reamer to the lower end thereof. Communicating with the upper end of said recess and arranged out of line with each other are vertical slots C, which open on opposite sides of the reamer. On opposite sides of the reamer are plates D, which form the outer sides of the recess B, and are secured at their upper ends to the body of the reamer by means of transverse bolts E. A block, F, is arranged in the lower end of the recess B, and is secured between the plates D by means of a transverse bolt, G.

H represents a pair of drill-bits, which are shaped as shown in Figs. 1 and 3, their inner sides or edges being angled, and are arranged in the upper end of the recess B and in the slots C, are in contact with each other, and are pivoted on a bolt, I, which passes also through the side plates, D. Said side plates are provided at a suitable distance below the

bolt I with vertical slots K, and on the inner edges of the bits, at the lower ends of the same, are recesses, which, when said lower edges of the bits come together, form a vertical opening, L.

M represents a follower-block, which is arranged in the opening B, and is secured and guided therein by means of a bolt, N, which passes through said block and works in the slots K. The said block is provided on its upper side with a pair of arms, O, the opposing edges of which are inclined in opposite directions, as shown, presented to the inner edges of the bits, and have right-angled recesses P at their lower ends, which receive the lower inner corners of the bit, as shown in Fig. 3.

R represents a coiled extensible spring, which is arranged in the lower end of the recess B and bears between the block F and the follower-block M, the function of the said spring being to raise the said follower-block normally to a position indicated in Fig. 3, and thereby cause said block to lock the bits H in the position shown in said figure and prevent the same from being retracted within the sides of the reamer.

On the outer sides of the plates D are arranged a pair of locking-plates, S. The said plates S are pivoted at a suitable distance from their lower ends on the ends of the bolt N, and in the upper end of each plate S, near one side of the same, is a vertical slot, T, the upper end of which is inclined, as shown, and has a shoulder, U. The ends of the bolt I operate in the slots T, and thereby cause the plates S to move vertically on the sides of the reamer with the follower-block M.

From the lower side of the block F depends a centering-stud, V. The upper end of the reamer has a threaded stem, W, which is adapted to be coupled to the drill-rod (not shown) in the usual manner.

The operation of my invention is as follows: In drilling Artesian and oil wells it is the custom to sink a casing-pipe, a, in the shaft as the same is bored until a stratum of rock is reached, the function of the casing-pipe being to line the shaft or well and prevent the sides of the same from caving in. In many instances the geological formation is such that

after the drill or reamer passes through the hard rock at the bottom of the pipe it encounters a substratum of shale interspersed with strata of gritty sandstone and hard lime-
5 rock. Such a formation renders it necessary to line the well or shaft all the way down, in some instances to a depth of two thousand feet. Heretofore when such a formation has been encountered it has been necessary to
10 withdraw the pipe already in the well and to substitute a larger reamer for the one in use, so as to re bore and enlarge the shaft or well through the hard rock to a sufficient diameter to admit the pipe.
15 My invention is designed to obviate the necessity of withdrawing the pipe by enabling the bits to be expanded laterally from the sides of the reamer when the latter is below the pipe, so as to enlarge the diameter of
20 the shaft.
The reamer is introduced originally into the shaft with its bits extended, as shown in Figs. 1 and 3, thereby enabling the reamer to bore an opening of sufficient diameter to receive
25 the casing-pipe. The said boring-bits are maintained in their extended position by the spring-actuated follower-block M, before described. When it is desired to withdraw the reamer from the shaft or well, the same is
30 raised until the projecting upper inclined corners, U', of the plates S come in contact with the lower end of the casing-pipe, when said plates S are caused to move downward on the reamer and force the follower-block M down-
35 ward therewith against the tension of the spring R, thereby releasing the said block from the boring-bits and permitting the latter to swing within the reamer-head, so as to reduce the diameter of the latter to less than the in-
40 ternal diameter of the casing-pipe, and thereby permit the ready withdrawal of the reamer through the said pipe, as will be readily understood. As the plates S move downward, their upper ends are moved inward when the
45 bolt I reaches the inclined upper portion of the

slots T, and the notches U at the upper ends of the said slots T engage the lower sides of the bolt I, and thereby lock the said plates, so that the spring cannot force the follower-block upward, consequently preventing the 50 bits from being expanded within the pipe and creating unnecessary friction therewith.

Having thus described my invention, I claim—

1. The combination of the reamer-head, the 55 bits H, pivoted therein and adapted to have their lower ends extended laterally therefrom, the spring-actuated follower-block guided in the reamer-head and adapted to lock the bits when the same are extended, and the verti- 60 cally-movable plates S, pivotally connected to the follower-block and having their upper ends adapted to engage the lower end of the well-tubing, substantially as described.

2. The combination of the reamer-head hav- 65 ing the vertical recess B in its lower side, the vertical slots C at the upper end of said recess and having the vertical slots K in its sides, the bits H, arranged in the slots C, the bolt I, extending through the sides of the reamer and 70 through the bits H to pivot the latter in the reamer, the spring-actuated follower-block M, adapted to engage the lower ends of the bits and lock the same in their extended position, said block having bolt N working in the slots 75 K, and the plates S, pivoted on the ends of the bolt N, bearing against opposite sides of the reamer, and having the slots T engaging the ends of bolt I, the upper ends of said slots being inclined in opposite directions, and said 80 plates S being further provided with the inclined upper corners, U', on their outer edges, substantially as described.

In testimony that I claim the foregoing as my own I have hereto affixed my signature in 85 presence of two witnesses.

WILLIAM WALLACE SWAN.
